MINIATURE SWITCH MECHANISM

Ernest R. Haberland, Los Angeles, Calif., assignor to Hughes Aircraft Company, Culver City, Calif., a corporation of Delaware

Application August 26, 1957, Serial No. 680,098

7 Claims. (Cl. 200—87)

This invention relates to switches and relates more particularly to miniature switches that are operable through disposition thereof in a magnetic field.

In low voltage dry circuit applications, i.e., arrangements employing $\frac{1}{10}$ volt or less and current in the order of a few microamperes, serious problems have heretofore existed and primarily caused by the normal formation of a layer of nonconductive metallic oxides on contact elements. Additionally, contact elements have frequently had foreign material deposited on the surfaces thereof and the presence of oxides and/or such foreign material prevents desired electrical conductivity between the contact elements. The foreign material may take the form of and be carried by various types of organic and inorganic vapors such as oil or water, as well as dust and other physical particles.

In order to operate such contacts in low voltage situations, and in order to maintain reliability in an ambient air atmosphere, several solutions to the normal problems have heretofore been used, such as creating high contact pressure whereby to crush through foreign matter or oxidation on contacts. Also, contacts have been provided with a long lever arm and structure to cause a wiping action between contacts, in order constantly to eliminate foreign material and polish off any oxidation that may have formed thereon. Both of these solutions cause excessive wear of the contact material, thus requiring the use of large mass contacts and/or requiring the use of heavy springs or other mechanical devices to establish the high contact pressure necessary, thus also requiring high operating forces.

Another solution to the problems heretofore presented resides in the disposition of the contacts in a fixed atmosphere usually created by the sealing of these contacts within an enclosure. Such enclosures have been filled with an inert material such as nitrogen gas, for example. In these instances light contact pressure may be employed and no crushing or wiping action between the contacts is necessary.

When sealing contacts within an enclosure, an additional problem arises, that of providing operating means for the contacts and maintaining the operating means at a size that is commensurate with use thereof in miniaturized electrical systems and components. For this purpose, sealed elongated glass envelopes, employing two or more reeds of magnetic material, have been employed, with the reeds being movable into contact with each other by disposition thereof in a magnetic field. Reed type switches are completely satisfactory for some installational situations; however, due to the construction thereof, they cannot be used in extremely miniaturized components as may be desired in computers and the like that must be carried as airborne equipment such as in aircraft, missiles, rockets and the like. The reed type switches must necessarily be relatively long and, when several of these switches are mounted circumferentially about an actuating magnet and several other banks thereof are placed in end to end relationship, the resulting

2

multiple switch structure becomes extremely large and completely incompatible with the small space envelopes available in particular installational situations. Additionally, due to the fact that reed type switches have a generally elongated configuration, the disposition of the reeds in the most advantageous position in a magnetic field, i.e., intermediate the poles of a magnet, becomes extremely difficult and, in some cases, impossible.

Accordingly, it is one object of the present invention 10 to provide a miniature switch mechanism that may be operated and used in low voltage, low current applications.

It is another object of the invention to provide a miniature switch mechanism that may be energized by disposition in a magnetic field.

A further object of the invention is to provide a magnetic switch mechanism employing contacts that are reliably operable with low contact pressure and no wiping action.

20 Still another object of the invention is to provide a miniature switch mechanism wherein contacts thereof have a relatively long life expectancy.

A still further object of the invention is to provide a magnetic switch mechanism having counterbalanced contacts disposed on free ends of resilient arms, whereby to reduce contact bounce or rebound and provide for positive action thereof.

25 A further object of the invention is to provide a miniature, magnetically operable switch mechanism having construction and assembly characteristics enabling efficient and economical manufacture thereof and reliable operating characteristics.

Another object of the invention is to provide miniature magnetically operable switch mechanism and an enclosure therefor.

Other and further important objects of the invention will become apparent from the disclosures in the following detailed specification, appended claims and accompanying drawing, wherein:

30 40 Figure 1 is a transverse sectional view through a typical, partially schematically illustrated, multiple switch apparatus employing the switch mechanisms of the present invention;

45 Fig. 2 is an enlarged transverse sectional view through the present switch mechanism and showing the contacts in an open position;

Fig. 3 is a sectional view similar to Fig. 2 showing the contacts in a closed position and diagrammatically showing the operating arrangement therefor;

50 Fig. 4 is a transverse sectional view of the switch mechanism as taken substantially as indicated by line 4—4, Fig. 2;

Fig. 5 is a greatly enlarged, partially sectional view of one of the contact elements and counterbalance arrangement therefor, as taken substantially as indicated by line 5—5, Fig. 4; and

Fig. 6 is an enlarged fragmentary sectional view of one of the resilient, contact carrying arms, as taken substantially as indicated by line 6—6, Fig. 2.

60 70 With reference to the drawing, the miniature switch mechanism of this invention is shown as indicated generally at 10. The present switch mechanism may be of any desired size; however, it has been found to be practical, and switches have been manufactured in a minute size in the order of $\frac{3}{16}$ " in diameter and $\frac{5}{16}$ " in length. The illustrations contained herein are all therefore greatly enlarged with one feature hereof residing in the particular construction enabling manufacture and use in miniaturized applications. For example, as shown in Fig. 1, it is often desirable to employ a number of switches in an electrical sequencing or switching structure. The structure shown in Fig. 1, by way of example,

comprises a housing 11 having a rotatable shaft 12 disposed therein. A plurality of the switch mechanisms 10 are carried by the housing 11 and extend into an inner cavity 13 thereof. As shown, the switches 10 are arranged in two banks of circumferentially spaced units; however, it is to be understood that any number of such switches may be disposed in a circumferential or other pattern and arranged in as many banks as desired without departing from the spirit and scope hereof.

The shaft 12 has a pair of permanent magnets 14 carried thereby and spaced both circumferentially and longitudinally on the shaft, each of the magnets 14 cooperating with one of the circumferential banks of switches 10. As will be later described, the poles of the magnets 14 serve to actuate contacts in the switches 10 as these poles are brought in coextensive alignment with such contacts by rotation of the shaft 12. In this connection it is to be understood that several magnets may be employed with each bank of switches 10 and may be spaced and arranged relative to each other longitudinally or circumferentially on the shaft to meet particular sequencing or switching requirements. Additionally, it is further to be understood that the switches 10 may be used individually rather than in groups to satisfy other operational requirements.

With reference now primarily to Figs. 2 through 6, the switch mechanism hereof comprises an annular metallic base member 15 having a shank portion 16 and an annular outwardly extending flange 17. The base member 15 may be made from any suitable material, is preferably nonmagnetic and has an integral annular V-shaped ridge 18 formed in an axial direction from the flange 17, for a purpose to be hereinafter more fully described.

The base member 15 is adapted to support a pair of metallic electrical leads 20 generally within a central area of a bore 21 therethrough. The leads 20 are rigidly retained within confines of the bore 21 by means of an insulating material 22 that may be glass or the like, the construction being such as to provide a hermetic seal between the surfaces of the leads 20 and the surface of the bore 21. The expansion coefficients between the materials of the base member 15, leads 20 and insulating material 22, are such as to provide compressive forces between these elements and to maintain the desired hermetic seal under changing ambient temperature conditions and like situations.

Each of the leads 20 terminates in an integral, generally rectangular portion 23 thereon and positioned adjacent an inner surface 24 of the insulating material 22. An arm 25 is secured to each of the rectangular portions 23, at least one of these arms being of resilient material. With reference to Figs. 4 and 6, it is to be noted that lower ends of each of the arms 25 are provided with outwardly extending portions 26 that are bent or wrapped about the rectangular portions 23 of the leads 20 and secured thereto as by means of a spot weld 27, thus firmly to secure the arms 25 to the leads 20, provide the desired electrical connection therebetween and maintain a rigid support for the lower ends of the arms 25. The arms 25 are made from a nonmagnetic material such as, for example, beryllium copper and are sufficiently resilient as normally to maintain the arms in a substantially parallel relationship relative to each other and as shown in Fig. 2.

The free ends of the arms 25 serve to support contact members indicated generally at 30. The contacts 30 are made from a highly permeable magnetic material such as an iron-nickel alloy and each have a head portion 31 and a reduced diameter elongated shank portion 32. The shank portions 32 are adapted for disposition in openings 33 in the free ends of each arm 25, and a counterbalance member 34, of magnetic material and in the form of an annular ring, is disposed about each of the shank portions. Each of the counterbalance members 34 has one end surface 35 that is disposed in contact with one

side of each of the arms 25. The free ends of the shank portions 32 have a recess 36, with the counterbalance members 34 being retained thereon and in contact with the arms 25 by upsetting an end of the shanks as at 37 over an end 38 of each of the counterbalance members 34. Thus, a shoulder 40 on each of the contact head portions 31 is also retained in tight contact with another side of each arm 25.

As shown primarily in Fig. 5, the head portions 31 of each of the contacts 30 are suitably rounded and are plated with a nonmagnetic material. The plating is preferably established in multiple layers, an inner layer 41 being, for example, stress-free nickel that may be suitably heat treated after plating, an outer layer 42 having high electrical conductivity as may be derived from material such as rhodium, for example. Thus, a contact structure is established wherein high electrical conductivity is maintained and peeling or chipping of the plating is minimized through the multiple layer plating technique. Additionally, when the contacts are in a closed position as shown in Fig. 3, the nonmagnetic nature of the plated layers 41 and 42 serve to provide a magnetic gap between the highly permeable head portions 31. This magnetic gap serves to control the dropout or separation time of the contacts when removed from a magnetic field. Thus, positive contact and subsequent release as between the contact members 30 is controlled and maintained.

As shown, the contacts 30 and arms 25, as well as inner ends 23 of the leads 20, are enclosed within a case 43 that may be made from any suitable nonmagnetic material such as, for example, silver or the like. The case 43 has an annular flange 44 adjacent an open end thereof, this flange being secured to the annular ridge 18 of the base member 15 as by projection welding, thus to create a hermetically sealed enclosure structure. A space 45 within the case 43 may also be filled with an inert material such as, for example, nitrogen gas or the like.

In operation of the present switch mechanism, as shown diagrammatically in Fig. 3, the poles of the magnets 14 are disposed in substantially coextensive alignment with the contacts 30. It is to be noted that the case 43 serves to establish and maintain a greater space between the poles of the magnet 14 and one end of the contacts 30, than the normal space between the contacts 30. Thus, the magnetic field induces opposite polarity in the counterbalance members 34 and heads 31 of the contacts 30 causing the heads to be moved toward and into contact with each other. Removal of the magnetic field serves to cause separation of the contacts by the resilient action of at least one of the arms 25. It is to be noted that the construction hereof is such as to dispose an elongated relatively large mass of magnetic material, forming the contacts 30, in line with the magnetic field disposed thereabout. This elongated structure serves to enable operation of the switch mechanism with a relatively low magnetic flux.

It is to be noted that the counterbalance members 34 serve to dispose the center of mass of each of the contacts 30 in line with the respective resilient arms 25, rather than at one side thereof, thus to create a continuous, pure arcuate bend of the arms 25, rather than any random bending thereof that would otherwise occur. This counterbalancing arrangement serves to reduce, and in most instances serves to eliminate any contact bounce that would otherwise cause undesirable electrical characteristics. This is particularly true with the application of magnetic operating forces directly to and coextensive alignment with the contact members 30, rather than through any type of lever system of the type usually employed in conventional heretofore known relays. Additionally, the spring force of at least one of the resilient arms 25 need only be very light to accomplish the desired results.

It may thus be seen that a reliable, efficient and effective miniature switch mechanism has been provided that

may be operated in installational situations requiring the use of a plurality of such switches arranged in a compact and miniaturized support. It may also be seen that this particular switch mechanism requires only small operating forces and may be used in low voltage applications, means being provided to eliminate corrosion of contact members and/or disposition of foreign materials on the contacts.

Having thus described the invention and the present embodiment thereof, it is desired to emphasize the fact that many further modifications, including more than two contact members, may be employed and resorted to in a manner limited only by a just interpretation of the following claims.

I claim:

1. A miniature switch mechanism comprising, in combination: a base member; an insulating material carried by said base member; a pair of leads disposed through and retained against movement in said insulating material; flexible metallic arms carried by inner end of said leads, said arms being disposed in spaced substantially parallel relationship; metallic electrical contacts of permeable material carried by free ends of said arms and disposed in facing spaced relationship to each other, said contacts having reduced diameter shank portions disposed through openings in said arms; counterbalance members disposed about said shank portions, an outer end of said shank portions being deformed to retain said counterbalance members thereon and in contact with said arms; and a protective case positioned in spaced relationship about said arms and said contacts, said case being secured to said base member, said contacts being adapted for movement into engagement with each other upon disposition thereof in a magnetic field.

2. A miniature switch mechanism comprising, in combination: a base member; an insulating material carried by said base member; a pair of leads disposed through and retained against movement in said insulating material; flexible metallic arms carried by inner end of said leads, said arms being disposed in spaced substantially parallel relationship; metallic electrical contacts of permeable material carried by free ends of said arms and disposed in facing spaced relationship to each other, said contacts having reduced diameter shank portions disposed through openings in said arms; counterbalance members disposed about said shank portions, an outer end of said shank portions being deformed to retain said counterbalance members thereon and in contact with said arms; and a protective case of nonmagnetic material positioned in spaced relationship about said arms and said contacts, said case being secured to said base member, said contacts being adapted for movement into engagement with each other upon disposition thereof in a magnetic field, said spacing between said contacts being less than said spacing between said contacts and said case.

3. A miniature switch mechanism comprising, in combination: an annular base member; an annular ridge on said base member; an insulating material carried by said base member; a pair of leads disposed through and retained against movement in said insulating material; flexible metallic arms of nonmagnetic material carried by inner end of said leads, said arms being disposed in spaced substantially parallel relationship; metallic electrical contacts of permeable material carried by free ends of said arms and disposed in facing spaced relationship to each other, said contacts having reduced diameter shank portions disposed through openings in said arms; counterbalance members disposed about said shank portions, an outer end of said shank portions being deformed to retain said counterbalance members thereon and in contact with said arms; and a protective case of nonmagnetic material positioned in spaced relationship about said arms and said contacts, said case being secured to said annular ridge on said base member, said contacts being adapted for movement into engagement with each other upon disposition thereof in a magnetic field.

contacts being adapted for movement into engagement with each other upon disposition thereof in a magnetic field, said spacing between said contacts being less than said spacing between said contacts and said case.

5. A miniature switch mechanism comprising, in combination: a base member; an insulating material carried by said base member; a pair of leads disposed through and retained against movement in said insulating material, inner ends of said leads extending beyond said insulating material and having generally rectangular cross sections; flexible metallic arms carried by said inner end of said leads and welded thereto, said arms being disposed in spaced substantially parallel relationship; metallic electrical contacts of permeable material carried by free ends of said arms and disposed in facing spaced relationship to each other, said contacts having reduced diameter shank portions disposed through openings in said arms; counterbalance members disposed about said shank portions, an outer end of said shank portions being deformed to retain said counterbalance members thereon and in contact with said arms; and a protective case positioned in spaced relationship about said arms and said contacts, said case being secured to said base member, said contacts being adapted for movement into engagement with each other upon disposition thereof in a magnetic field.

6. A miniature switch mechanism comprising, in combination: an annular base member; an annular ridge on said base member; an insulating material carried by said base member; a pair of leads disposed through and retained against movement in said insulating material, inner ends of said leads extending beyond said insulating material and having generally rectangular cross sections; flexible metallic arms of nonmagnetic material carried by said inner end of said leads and welded thereto, said arms being disposed in spaced substantially parallel relationship; metallic electrical contacts of permeable material carried by free ends of said arms and disposed in facing spaced relationship to each other, said contacts having reduced diameter shank portions disposed through openings in said arms; counterbalance members disposed about said shank portions, an outer end of said shank portions being deformed to retain said counterbalance members thereon and in contact with said arms; and a protective case of nonmagnetic material positioned in spaced relationship about said arms and said contacts, said case being secured to said annular ridge on said base member, said contacts being adapted for movement into engagement with each other upon disposition thereof in a magnetic field, said spacing between said contacts being less than said spacing between said contacts and said case.

7. A miniature switch mechanism comprising, in combination: an annular base member; an annular ridge on said base member; an insulating material carried by said

base member; a pair of leads disposed through and retained against movement in said insulating material, inner ends of said leads extending beyond said insulating material and having generally rectangular cross sections; flexible metallic arms of nonmagnetic material carried by said inner end of said leads and welded thereto, said arms being disposed in spaced substantially parallel relationship; metallic electrical contacts of permeable material carried by free ends of said arms and disposed in facing spaced relationship to each other, said contacts having reduced diameter shank portions disposed through openings in said arms; multiple plated coatings of a non-magnetic metallic material on said contacts; counterbalance members disposed about said shank portions, an outer end of said shank portions being deformed to retain said counterbalance members thereon and in contact with said arms; and a protective case of nonmagnetic material positioned in spaced relationship about said arms and

5

said contacts, said case being secured to said annular ridge on said base member, said contacts being adapted for movement into engagement with each other upon disposition thereof in a magnetic field, said spacing between said contacts being less than said spacing between said contacts and said case.
